GERMICIDAL DETERGENT

Milward Bayliss, Hurlock, Md., and John L. Wilson, St. Paul, and Erling J. Ordal, Minneapolis, Minn., assignors to Economics Laboratory Inc., St. Paul, Minn., a corporation of Delaware

No Drawing. Application May 10, 1935,
Serial No. 20,766

3 Claims. (CL. 167—14)

This invention relates to improvements in germicidal detergent compositions and includes such compositions in a concentrated or dry state, such as a dry powder, as well as germicidal solutions of such compositions.

The new compositions are valuable for use in homes, hotels, restaurants, hospitals and institutions, as well as in the beverage and dairy industries, where a germicidal action as well as a 10 detergent action is desired.

The new germicidal detergent compositions are in general admixtures of alkalies or buffer salts and wetting agents of the character hereafter referred to, in such proportions that when, for 15 example, a solution is made of the composition containing from $\frac{1}{2}\%$ to 3% of the composition the solution will have a high pH value, in excess of about 11.5.

The buffer salts which are used in the new 20 composition are alkaline salts or alkalies, such as carbonates, phosphates or silicates, etc., used in such amounts and proportions as will give to the final solution the desired pH value. Among such buffer salts may be mentioned sodium carbonate, mono-sodium-phosphate, di- 25 sodium phosphate, tri-sodium phosphate, sodium silicates, etc.

In using these buffer salts, in making the new 30 composition, the proper pH is obtained by a selection of the buffer salts employed which may, in some cases, be a single salt or salts of the same acid, or salts of different acids, etc. For example, the proper pH may be obtained by the use of a mixture of various phosphates and carbonates, or various phosphates and silicates, or 35 carbonates and silicates, or by mixtures of phosphates, carbonates and silicates; as well as by mixtures of various phosphates alone, or carbonates alone, or silicates alone. Similarly, other salts besides phosphates, carbonates and silicates 40 may be used to obtain the proper pH.

The wetting agents which are used, together 45 with the alkaline salts, in making the new compositions, are in general wetting agents of a character which are superior to and distinguished from ordinary soap. Among the important wetting agents which are employed in accordance with the present invention, are sulfonated products such as sulfonated hydrocarbons or sulfonated higher alcohols and sulfonated oils which 50 are free from a carboxyl (free or neutralized) group or which have a carboxyl group blanched or made ineffective. Certain phenolic or alcoholic wetting agents are also included.

The sulfonated higher fatty alcohols have recently been introduced in commerce as wetting 55 agents and these are well adapted for use in the new composition of the present invention. The

higher alcohols are obtainable by catalytic reduction, under proper conditions, from the fatty acids of natural fats and their esters. When sulfonated with concentrated sulfuric acid under proper conditions they yield products known in the trade as fatty alcohol sulfates or half sulfuric acid esters of the fatty alcohols. While referred to as sulfonated fatty alcohols, they are more properly referred to as alkyl esters of sulfuric acid having for example the general 10 formula $R.O.SO_2.ONa$, where R is a straight chain aliphatic radical containing 8 or 10 carbon atoms or more. A simpler formula for these sulfonated fatty alcohols is $R.SO_4.Na$, representing the sodium salts of the alkyl sulfates, where R 15 is a long chain aliphatic radical. Among these sulfonated fatty alcohols may be mentioned sodium lauryl sulfate, sodium octadecyl sulfate, and sodium oleyl sulfate. The technical grade of sulfonated lauryl alcohol is known as sulfonated 20 Lorol and the technical grade of sulfonated oleic or oleyl alcohol is known as sulfonated Ocenol. Where the alcohol sulfonated is an unsaturated alcohol the sulfuric acid may react by addition at the double bond to form sulfonic or sulfate derivatives as well as by reaction with the hydroxyl group to form the ester. The products 25 may be in part true sulfonic acids or may contain true sulfonic acids as well as sulfates or sulfuric acid esters. When chloro-sulfonic acid is used for sulfonating the unsaturated alcohols true 30 sulfonic acids are produced and where the alcoholic hydroxyl is converted into a sulfate the sulfonated alcohol may contain both a sulfonic and a sulfate group. The sulfonated higher alcohols are marketed under various trade names, 35 such as Gardinols, Brilliant Avirols, Orvus, Dreft, etc. The sodium oleyl sulfate, for example, is marketed under the trade name Gardinol CA and the lauryl sodium sulfonate is marketed under 40 the trade name Gardinol WA. The higher fatty alcohol sulfonates derived from stearyl and cetyl alcohols are marketed under the trade names Brilliant Avirols L142, L144 and L168. These various sulfonated alcohol products are used in 45 the form of their sodium salts.

The sulfonated higher alcohols, although produced by the sulfonating of the alcohols, are in their nature sulfonated hydrocarbons or hydrocarbon sulfates and may be referred to as alkyl 50 sulfates.

Other sulfonated hydrocarbon wetting agents can also be used in the new composition of the present invention such as the alkyl naphthalene sulfonic acids sold in the trade as Nekals, Perminals, Merpentine and Alkanol B. Substituted naphthalene sulfonic acids are also sold under the trade name Oranit. Isopropyl naphthalene 55

sulfonic acid is sold under the trade names Neomerpin, Erkalin and Alkanol SA. The alkylated naphthalene sulfonic or sulfuric acid products are used in the form of their sodium salts, for example, the sodium isopropyl naphthalene sulfonate. Other sulfonated hydrocarbons are represented by sulfonated abietenes, or sulfonated abietanes, for example, sodium abietene sulfonate; or the sodium salt of sulfonated abietanes (hydrogenated abietenes). The naphthalene sulfonic acid compound may be combined with one of the fatty sulfonic acid compounds, as in Oranit BN Extra. The sodium salts of naphthalene sulfonic acid derivatives are also marketed under the trade name Alkanol. Sodium tetralin sulfonate is also marketed under the trade name Alkanol S. Sodium tetrahydro naphthalene sulfonate is the active wetting agent in Alkanol PF.

Certain sulfonated wetting agents are made from oleic acid and isethionic acid. The product having the formula

is sold under the trade name Igepon A. A somewhat different product having the formula

is sold under the trade name Igepon T. Igepon T in a solvent is sold under the trade name Laventine KB. The sodium salt of the oleic acid ester of isethionic acid is sold under the trade name of Igepon AP.

Wetting agents derived from ricinoleic acid by sulfonation and with the hydrogen of the carboxyl group blanketed to render it ineffective are represented by the sodium salt of the sulfuric ester of butyl ricinoleic ester.

sold in the trade as Avirol AH Extra. Sulfonated fatty oils are sold under the trade names Nopco Castor and Intrason.

The sodium salt of the sulfuric ester of oleic acid amide is sold under the trade name Humectol C.

The various wetting agents are used in the new composition in the form of their sodium salts together with the buffer or alkaline salts in such proportions that there will be present in the solution made of the composition only a small percentage of the wetting agent together with such amount of the buffer salt as will give to the solution a high pH value of around 11.5 or higher. While the wetting agents themselves are relatively ineffective as germicides, the compositions in which they are used together with the alkaline salts are highly effective, such that solutions from the new compositions are excellent detergents and exhibit sufficient germicidal properties so that they can also be used as germicides. In general the solutions made from the new compositions will contain from around 1/2% to 3% of the composition, although the amount can be somewhat varied.

The new compositions are advantageously compounded and marketed in the form of a dry powder containing the wetting agent, where available in a dry powdered form, together with the pulverulent alkaline salt, in the form of an intimate and substantially homogeneous mixture, such that a definite weight of the powdered composition can be used to give a solution of definite strength and proportions of the different ingre-

ients. Such a dry mixture of the ingredients can be readily produced, handled, shipped and stored and a definite amount measured or weighed out for use in producing germicidal detergents.

The particular alkali salt or salts used in the composition for giving it the desired high pH value can be varied and are best defined by the pH value of the resulting solution rather than by attempting to give the various combinations of chemicals which will provide the desired high pH value.

In testing the solutions of the new composition, we have used the following test: The dry mixture, containing the ingredients of the composition, is made into a solution of from 1/2% to 3% strength. To 5 cc. of this solution is added 1/2 cc. of a 24 hour culture of the standard test organism, *Staphylococcus aureus* (Insecticide Board strain). Before the culture is added to the test solution, it is brought to the required temperature; the temperature we have used has been 37° C. or in some cases a higher temperature. After the culture has been in the test solution for five minutes, a 4 mm. loopful is removed and added to a tube of molten agar at a temperature of 45° C. and the mixture is poured into a Petri plate. The plates are incubated for 48 hours, at the end of which time a count is made of the colonies appearing on the plate. The number of organisms originally added to the test solution is in the neighborhood of five hundred millions (500,000,000). If no organisms are killed, the loopful removed will contain an excess of 10,000 organisms, and therefore the number of colonies appearing on the plates will be in excess of 10,000. If some of the organisms are killed, the number of colonies appearing on the plates will be less than 10,000. In the data reported in the following examples, the numbers indicate the colonies appearing on the test plate after 48 hours of incubation. Similar tests were made using *Eberthella typhi* (Hopkins strain).

As illustrating the action of water alone, sodium lauryl sulfate alone, in various amounts, sodium carbonate, trisodium phosphate, sodium meta-silicate and sodium sesqui-silicate, the following table gives the results of tests made as above described, with these various substances, the tests being carried out with *Staphylococcus aureus* (F. D. A. strain) at a temperature of 37° C. and with a plate count after 5 minutes and 10 minutes respectively. The organism employed and the temperature and time of the test are in accordance with the standards adopted by the Federal Food and Drug Administration (F. D. A.):

Solution tested	Plate counts		60
	5 min.	10 min.	
Water alone	10,000+	10,000+	
0.01% sodium lauryl sulfate	10,000+	10,000+	
0.1% sodium lauryl sulfate	10,000+	10,000+	65
1.0% sodium lauryl sulfate	10,000+	10,000+	
2.0% sodium lauryl sulfate	10,000+	10,000+	
1% sodium carbonate (Na_2CO_3) (pH = 11.4)	10,000+	10,000+	
2% sodium carbonate (Na_2CO_3) (pH = 11.5)	10,000+	10,000+	
1% T. S. P. (trisodium phosphate) ($\text{Na}_3\text{PO}_4 \cdot 12\text{H}_2\text{O}$) (pH = 12.0)	10,000+	10,000+	
2% T. S. P. (trisodium phosphate) ($\text{Na}_3\text{PO}_4 \cdot 12\text{H}_2\text{O}$) (pH = 12.2)	3,000+	3,000+	70
2% Metso (sodium metasilicate) ($\text{Na}_2\text{SiO}_3 \cdot 5\text{H}_2\text{O}$) (pH = 12.6)	1,800	900	
1% Metso (sodium metasilicate) ($\text{Na}_2\text{SiO}_3 \cdot 5\text{H}_2\text{O}$) (pH = 12.3)	10,000+	8,000+	
1% Metso 99 (sodium sesquisilicate (pH = 12.6))	2,000	800	

From this table it will be seen that the various alkaline salts alone are ineffective at this temperature and in these concentrations as germicides and that the sodium lauryl sulfate is likewise ineffective. However, when sodium lauryl sulfate or other effective wetting agents, such as those above referred to are used in combination with the alkaline salts, a pronounced germicidal action as well as detergent action is obtained. The germicidal action of sodium lauryl sulfate in various amounts used together with trisodium phosphate and sodium meta-silicate (Metso) are illustrated by the following table, the organism used, the temperature, etc., being those above referred to:

	Solution tested	Plate counts	
		5 min.	10 min.
20	2% T. S. P. + 0.01% sodium lauryl sulfate	200	20
	2% T. S. P. + 0.05% sodium lauryl sulfate	120	2
	2% T. S. P. + 0.02% sodium lauryl sulfate	0	0
	2% T. S. P. + 0.05% sodium lauryl sulfate	0	0
	2% T. S. P. + 0.1% sodium lauryl sulfate	0	0
25	2% T. S. P. + 0.5% sodium lauryl sulfate	0	0
	1% Metso + 0.1% sodium lauryl sulfate	0	0
	1% Metso + 0.05% sodium lauryl sulfate	0	0
	1% Metso + 0.02% sodium lauryl sulfate	80	3
	1% Metso + 0.015% sodium lauryl sulfate	125	15
	1% Metso + 0.01% sodium lauryl sulfate	400	100
30	2% Metso + 0.1% sodium lauryl sulfate	0	0
	2% Metso + 0.05% sodium lauryl sulfate	0	0
	2% Metso + 0.02% sodium lauryl sulfate	0	0
	2% Metso + 0.015% sodium lauryl sulfate	0	0
	2% Metso + 0.01% sodium lauryl sulfate	7	0

These results are to be compared with the action of phenol solutions used as control where the following results were obtained:

	Solution tested	Plate counts	
		5 min.	10 min.
40	1% phenol	0	0
	1/2% phenol	0	0
45	1/100 phenol	30	0

The results of tests made as above described with compositions made with various wetting agents and with sodium meta-silicate or sodium carbonate, in accordance with the tests above referred to are given in the following table:

	Solution tested	Plate counts	
		5 min.	10 min.
55	Water alone	10,000+	10,000+
	1% Metso (sodium metasilicate) (Na ₂ SiO ₃ ·5H ₂ O) (pH=12.3)	10,000+	3,000
60	1% Metso + 1% Erkalin	125	15
	1% Metso + 2% Erkalin	0	0
	1% Metso + 1% Alkanol B	200	30
	1% Metso + 2% Alkanol B	5	0
	1% Metso + 2% Merpentine	6	0
	1% Metso + 2% Alkanol SA	15	3
	1% Metso + 2% Orvus (sodium lauryl sulfate)	20	0
	1% Metso + 0.2% sodium stearyl sulfate	40	0
65	1% Metso + 0.2% Alkanol PF	40	0
	1% Metso + 0.2% Laventine KB	125	2
	1% Metso + 0.2% sodium oleyl sulfate	250	3
	1% Metso + 0.2% Humectol C	300	5

70 Another series of tests made with compositions containing sodium meta-silicate and a fraction of a percent of various wetting agents is indicated by the following table, the temperature maintained in these tests being 45° C. and the same organism being used as in the tests

above referred to, the last three solutions representing phenol solutions used as control:

Solution tested	Plate counts	
	5 min.	10 min.
2% Metso (sodium metasilicate) (Na ₂ SiO ₃ ·5H ₂ O) (pH=12.6)	3,000	700
2% Metso + 2% Erkalin	0	0
2% Metso + 2% Humectol C	0	0
2% Metso + 2% Igepon T	0	0
2% Metso + 2% Igepon AP	0	0
2% Metso + 2% Intrasol	0	0
2% Metso + 2% Laventine KB	0	0
2% Metso + 2% Nopco Castor	0	0
2% Metso + 2% Orvus	0	0
1/10 phenol used as control	2	0
1/10 phenol used as control	25	0

From the above examples it will be noted that the solution tested contained only a small fraction of a percent of the wetting agent and only around 1 or 2% of the total composition, but the solution was nevertheless effective as a germicide in addition to its detergent properties.

The wetting agents used in the composition impart improved penetrating properties to the composition, making the composition effective in its detergent as well as its germicidal properties. In general the amounts of wetting agents will be around 0.002% or higher, the amount to be used in practice depending on the wetting agent used, on the pH of the solution, on the temperature of the solution, and on the length of time of contact with and the kind of organisms to be killed. In general the amount of the wetting agent will form only a small proportion of the dry mixture, where the composition is prepared and marketed in dry form, the greater part of the composition being made up of the alkaline or buffer salts of such nature and amount as will impart to the solution of the composition the desired high pH value.

The new compositions are useful for many purposes as in hospitals or institutions, where germicidal detergents are important, as well as in hotels and restaurants for dish-washing and other purposes, and in various industries such as the beverage and dairy industries, where it is important, for example, to sterilize the bottles and containers as well as to wash them.

In some cases it is advantageous to use a plurality or mixture of active wetting agents, instead of only one active wetting agent, in the new composition. The active wetting agents differ somewhat in their detergent or sudsing properties, and it is sometimes advantageous to add a wetting agent which is less ineffective in the germicidal properties which it imparts to the composition together with another active wetting agent which is more effective, thereby obtaining a balance in antiseptic and detergent properties by the use of two or more active wetting agents which differ somewhat from each other in their properties, or one of which, though more effective, is more expensive, and can be advantageously used in smaller amounts together with one or more other active wetting agents. It will be understood that, where a mixture or plurality of active wetting agents is used, the alkali salt, or mixture of alkali salts used to give to the solution the high pH value, can be varied, and a single salt, or a mixture of salts, used, in such proportions as will insure in the resulting solution the desired high pH value.

By the term "wetting agents" we mean those

wetting agents which are sulfonated products such as sulfonated hydrocarbons or sulfonated higher alcohols, and which are free from carboxyl groups, whether free or neutralized, or which have carboxyl groups blanked or made ineffective in a suitable manner, as by substituting for the hydrogen of the carboxyl group an alkyl group, or an amido group, or other suitable group and which do not form objectionable precipitates with calcium and magnesium ions found in hard water, as distinguished from ordinary soaps, which are neutralized carboxylic acids and which form objectionable precipitates with calcium and magnesium ions present in hard water.

15 We claim:

1. A germicidal detergent composition comprising a sulfonated alcohol wetting agent and alkaline salts in such proportions that an aqueous solution containing from $\frac{1}{2}$ to 3% of the composition will have a pH value in excess of about 11.5 and will contain a small fraction of 1% of the sulfonated alcohol.

2. A germicidal detergent composition comprising sodium lauryl sulfate and alkaline salts in such proportion that an aqueous solution containing from $\frac{1}{2}$ to 3% of the composition will contain a small fraction of 1% of the sodium lauryl sulfate and will have a pH value in excess of about 11.5. 5

3. A germicidal detergent composition containing a major proportion of buffer salts and containing a relatively small proportion of a mixture of active sulfonated wetting agents, including a sulfonated alcohol wetting agent, said composition being adapted when dissolved in water in amounts ranging from $\frac{1}{2}$ to 3% to form a germicidal detergent solution containing 15 a small fraction of 1% of the wetting agents with a sufficient amount of the alkaline salts to give a pH value in excess of about 11.5.

MILWARD BAYLISS. 20
